UNITED STATES PATENT OFFICE

JOHN J. MURRAY, OF YONKERS, NEW YORK

DISPLAY DEVICE

Application filed August 19, 1931. Serial No. 558,143.

This invention relates to display devices designed for use for advertising purposes, and particularly to display devices of the self-supporting type and formed of card-
5 board or other analogous or suitable material.

One object of the invention is to provide a display device for displaying advertising or reading matter which may be formed from a normally flat shape into a shape and appearance 10 simulating a book, boat, building or other suitable and desired object.

A further object of the invention is to provide a display device which may be die cut or otherwise cut into the primary shape of 15 a normally flat blank, so as to be conveniently packed with others of its kind for storage or transportation, and which may be readily shaped from blank form to produce a set up display device.

20 A still further object of the invention is to provide an article of this character which will embody horizontal and upright supporting portions adapted to be interengaged or interlocked to firmly support the display surfaces of the device at an appropriate angle.

A still further object of the invention is to provide an article of the specified character which may be made of a very attractive and 30 ornamental design and yet manufactured and sold at a comparatively low cost.

35 A still further object of the invention is to provide a display device the display surfaces of which may be changed whenever desired by the use of supplementary cards or sheets applied to and utilizing the primary display device as a supporting stand or holder.

With these and other objects in view, the 40 invention consists of the features of construction, combination and arrangement of parts, hereinafter fully described and claimed, reference being had to the accompanying drawings, in which:—

Fig. 1 is a view showing a set up display 45 device embodying my invention and of a construction to simulate an open book supported for display in an upwardly inclined position.

50 Fig. 2 is an end elevation of the set up display device shown in Fig. 1.

Fig. 3 is a rear elevation of the same.

Fig. 3a is a section on line $x-x$ of Fig. 2.

Fig. 4 is a view of the flat blank from which a display device of the type shown in Figs. 1, 2 and 3 is made, differing therefrom 55 only in the illustrated pictorial matter.

Fig. 5 is a view similar to Fig. 1 showing the application of a supplementary sheet to a primary display device.

Fig. 5a is a section on the line $y-y$ of 60 Fig. 5.

Fig. 6 is a view similar to Figs. 1 and 5 showing a display device of different form, that is, of acorn form instead of a book.

Figs. 7 and 8 are views showing the use 65 of a fastening connection between the standard and base support.

In carrying my invention into practice I provide an advertising device comprising a unitary blank 1, shown in Fig. 4 in normally 70 flat or unfolded condition, and which is preferably die cut from cardboard or other suitable sheet material of proper thickness. This blank, in the form shown in Figs. 1 to 5, inclusive, consists of a rectangular or oblong rectangular body portion cut out and scored to provide a pair of oppositely extending wings 2 and 3, an intermediate folding section 4, and a base portion or section 5, which base portion is constructed and scored 75 to provide wings 6 and 7 and an intermediate folding portion 8 forming continuations, respectively, of the lower edges of the portions 2, 3 and 4 of the sheet body.

The portion or section 4 is separated from the wings 2 and 3 by vertical score lines 9 and 10 and is provided with a central score line 11 arranged equidistantly between and parallel with the first-named score lines. Other score lines 12 start from the line 11 a short distance from the top of the card and extend divergently upwardly to and intersect the upper ends of the lines 9 and 10 and form a double triangular folding portion 13 at the top of the section 4. At their upper edges the wings 6 and 7 are separated from the lower edges of the wings 2 and 3 by score lines 14 and 15, and said wings 6 and 7 are separated from the intermediate folding section 8 by score lines 16 and 17 which form 85 90 95 100

continuations of and intersect the score lines 9 and 10, and between the score lines 16 and 17 the section 8 is provided with an intermediate score line 18 which is in alignment with the score line 11. Score lines 19 similar to the score lines 12 intersect the score lines 16 and 17 at the lower edges of the wings 6 and 7 and extend upwardly in convergent relation and intersect slits 20, thus forming 10 a folding portion 21 having a tongue 22 formed by a portion thereof produced by the slits 20, for a purpose hereinafter described. At the base of the center of the body of the card is a quadrangular slot or opening 23 15 separating the lower edge of the section 4 from the upper edge of the section 8 and extending equally into said sections.

The blank made as shown in Fig. 4, and of that shape or any other described shape, provides a folding display card adapted to be formed to represent a given object and having the front faces of its wings 2 and 3 forming display surfaces which may be suitably printed to bear any desired pictorial or reading matter, or both. In the exemplified illustration in Figs. 1 to 4, inclusive, the display surfaces of the wings are printed to represent exposed leaves of an open book, below which the margins of other simulated leaves show, which exposed leaves may be printed to simulate leaves of any published book or to display advertising matter suitable for any intended advertising purposes. This book is designed to be folded so as to form a

35 set up display device of self-supporting type which may be arranged in the window of a store or in any other place or position for display purposes, to display informative matter or to advertise any given commodity. In 40 folding the blank to produce the self-supporting display device, the center of the blank is folded centrally along the score lines 9-16, 10-17 and 11-18 to produce an upper doubled portion formed by the folded part 4 and 45 a lower doubled portion formed by the folded part 8, said parts being projected rearwardly along the central score lines 11 and 12 so that the portions of the blank along the fold lines 9 and 10 and 16 and 17 respectively, are 50 brought together or in close relative juxtaposition. By this means the wings 2 and 3 and portion 4 will be disposed to simulate the exposed leaves and intervening binding portion of the leaves of an open book and with the portion 4 arranged to serve as a holder or supporting standard for the leaves. At the same time the folding of the part 8 will produce at the bottom of the display device a double supporting flange. When the card is folded 55

60 in the manner described the wings 6 and 7 with their doubled portion 8 may be turned backward along the score lines 14 and 15 and projected so as to lie horizontally in rear of the wings 2 and 3 so as to cooperatively 65 provide a horizontal supporting stand for

the display device which may rest upon the floor of the window, a desk or other supporting surface. The triangular slot 23 allows the parts 4, 6, 7 and 8 to be readily bent, folded or doubled in the manner described and leaves the doubled portions 4 and 8 free at their adjacent end edges. As a result, the standard 4 may be moved backward at an angle to dispose the leaves or wings 2 and 3

70 in a suitable upwardly and rearwardly inclined position for an effective display, and in this operation the lower portion of the folded standard 4 may be disposed to lap over upon one side of the folded flange 8. When

75 so disposed the rear of the standard 8 may be moved into a keeper recess produced by the slits 20 and by bending the folded tongue 22 laterally, whereby the standard 8 will be

80 disposed and clamped between the standard 4 and tongue 22, thus stably holding the simulated book in display position. The folds of the standard 4 may be united by fastening means to keep the inner edges of the leaves 2 and 3 close together and from gaping, but, in

85 order to avoid the necessity of employing auxiliary fasteners, the folding portion 13 is provided which may be turned over on the score lines 12 to form a locking fold at the top of the standard 4, as will be readily understood.

90 When the standard 4 is engaged with the keeper recess 20 and tongue 22 the folds of the flange 8 will be held snugly together and such folds and the wings 6 and 7 held from spreading.

95 As stated, the display card constructed as above described may be employed to simulate an open book of any size, which is of self-supporting type and may be arranged in a

100 show window or other appropriate place for display and for the purpose of giving any certain information or advertising any cer-

105 tain product or products. When so disposed it will be held securely in position by its sup-

110 porting means which may be arranged so as to be concealed from view, so that the set up article, when properly printed or printed and engraved, will very closely resemble an actual book opened to display certain leaves. The leaves so displayed may bear reading and pic-

115 torial matter of any suitable kind to give the necessary information or to advertise a cer-

120 tain product in a desired way. To increase the effectiveness of the display, a false book mark of silk or other material may be prop-

125 erly arranged and draped and other accessories may be used, if desired, to enhance the attractiveness of the display. The construc-

130 tion of the article in the primary form of a flat blank allows a large number of blanks to be closely packed for storage or shipment and adapts the blank to be set up for use individually by the user in an easy and simple manner, so that an advertising or display article which is inexpensive of production and installation is produced.

The display device, while adapted for primary use for display purposes, may be employed as a holder for supplementary sheets 24, as shown in Figs. 5 and 5a, each sheet 24 being made of some thin flexible material conforming in construction to the leaves 2 and 3 and adapted to overlie the same and provided with a central folding or binding portion 4a, similar to the fold 4, which may be arranged to lie between the sides of the fold 4 and to be clamped thereby in position. By this means the advertising or display matter of a display device in use may be changed without discarding such display device, and by using the same as a holder for a supplementary sheet overlying the same, which may bear other display matter, and the advertising matter may thus be changed from time to time by the use of supplementary leaves so that the same general style of advertising matter may be kept up indefinitely if desired.

The shape and appearance of the display card or device may be changed within widely varying degrees and the card given different forms and appearances to suit many and varied purposes. One example of many possible is shown in Fig. 6 in which the card or display device 1a is shaped and pictorially depicted to represent a supported acorn, said device being shown in folded or set up condition and having the leaves or wings 2a and 3a, center fold or standard 4b, horizontal base supporting wings 6a and 7a and supporting flange 8a, and associated features illustrated and described with reference to Figs. 1 to 5, inclusive. Similarly an advertising device in the form of a diamond, heart, spade or club, or a boat, building, animal or other object may be formed, and other changes of similar character made within the scope of the appended claims without departing from the spirit or sacrificing any of the advantages of the invention. It will, of course, be understood that the wings or leaves forming the display surfaces need not be of the same size but may be, if desired, of different sizes and structurally formed and printed to represent various objects. The wings or leaves, for example, may be of different lengths, or different heights, or both, as required in the formation of different objects, and my invention is, therefore, not limited in any of these respects.

If desired, suitable means may be provided to mechanically fasten the standard 4 to or interlock said standard 4 with the flange 8 of the base support so as to obviate liability of casual disengagement of the same. One type of means for this purpose is shown in Figs. 7 and 8 wherein, in addition to the keeper recess 20 and tongue 22, the flange 8 is provided with punched out slots 24 and the standard 4 with punched out laterally-bendable locking tongues 25 to engage said

slots. Other types of fastening means for the purpose may be employed instead of slots and tongues and other means of fastening the folds of the standard at their upper ends may be employed in lieu of the bendable part 13.

What I claim is:—

1. A display device comprising a card having oppositely extending wing portions forming display surfaces, an intermediate foldable portion forming a supporting upright, and a base portion cooperating with the upright to form a supporting stand for the wings. 70

2. A display device comprising a card having oppositely extending upright wings or leaves, a foldable portion between the leaves adapted to be projected rearwardly of the plane thereof to form a supporting upright, horizontal wings or leaves at the lower edges of the upright leaves adapted to be projected rearwardly to form a supporting base, and a folding portion between the horizontal leaves and providing a supporting flange, said upright and flange having engaging surfaces for interconnecting the same to support the upright leaves in display position. 80

3. A display device comprising a card having oppositely extending upright main wings, a foldable portion between the main wings adapted when in folded position to form a supporting upright, horizontal wings at the lower edges of the upright wings adapted to be bent at an angle thereto to form a supporting base, a folding portion between the horizontal wings adapted when folded to form an upright supporting flange, the said folding portions between the wings being separated by a quadrangular slot whereby said portions are separated for a lapping action when the device is set up, the standard and flange having surfaces adapted for engagement to support the display wings in an inclined position. 90

4. A display device comprising a blank having oppositely extending upright main wings, horizontal wings at the lower edges of the main wings adapted to be bent at an angle thereto to form a supporting stand therefor, a folding portion between the main wings adapted when folded to form a supporting upright, a folding portion between the horizontal wings adapted when folded to provide a supporting flange extending upright from said wings, the said folding portions being separated by a quadrangular slot leaving their adjacent edges free from each other, and retaining means on the flange adapted to be engaged by the lower end of the supporting upright to hold the main wings in display position. 100

5. A display device comprising a card having oppositely projecting main wings, a folding portion between the main wings adapted to be doubled to form a supporting upright, horizontal wings at the lower edges of the 110

- main wings adapted to be bent at an angle thereto to form a support therefor, a folding portion between the horizontal wings adapted to be doubled to form an upright supporting flange when the horizontal wings are in supporting position, said folding portions of the main and horizontal wings being separated by a slot to permit folding of the foldable portions and adapt the lower end of the upright to be disposed at one side of the flange in the operative position of the display device, the said flange having a slotted portion providing a keeper to receive the upright and a tongue cooperating therewith to hold the upright from displacement.
6. A display device having main upright wings, a folding portion between the wings adapted to be doubled to form a supporting upright therefor, a supporting base carried by said wings, the upright and base having means for connection to support the wings in an inclined position from the base, and a supplemental sheet comprising leaves adapted to overlie the wings and provided with a folding portion between said leaves adapted to be received within and held by the folding portion of the wings.
7. A display device having main upright wings, a portion between the wings adapted to be folded to form a supporting upright, a supporting base carried by said wings, and fastening means for connecting said upright with said base.
8. A display device having main upright wings, a portion between the wings adapted to be folded to form a supporting upright, a supporting base carried by the wings and having an upstanding flange, the upright and flange having retaining means for supporting the wings in an inclined position from the base, and fastening means for securing the upright to the flange.

In testimony whereof I affix my signature.
JOHN J. MURRAY.
